ATTORNEY

UNITED STATES PATENT OFFICE

LOTT R. TRACY, OF SEATTLE, WASHINGTON

WEED KILLER

Application filed September 18, 1930. Serial No. 482,745.

My invention relates to improvements in weed killers of the variety wherein a fluid such as gasoline is utilized in destroying weeds by injecting it into the roots thereof.

5 The objects of the invention, stated in a general way, are:

To provide a device of this character in which the usual built-in container for said fluid is eliminated, the container in this device consisting of an ordinary glass bottle such as is found in every household or which may be easily supplied by the user, with the result that the device may be marketed without a container for the fluid, thereby simplifying such a device, reducing its cost of manufacture, and lessening its weight and bulk;

10 To afford instrumentalities, including valve mechanism, associated with said bottle, and means for supporting the instrumentalities and bottle in place, whereby the root of a plant may be crushed and a definite quantity of said fluid may be released from the bottle and conveyed into said root at one 15 operation; and,

To make available a weed killer of a length which will permit it to be used by an adult without stooping, yet so constructed that it may be disassembled and placed in a package of convenient size for retailing purposes or for carrying.

20 In the accompanying drawing—

Figure 1 is a side elevation of the device complete, said bottle having been installed therein.

25 Fig. 2 is a vertical section of a valve member mounted over the neck of said bottle, the bottle being sectionized and broken away, a supporting rod for said member and bottle also being shown, the same appearing partly in section and broken away.

30 Fig. 3 is a cross section drawn on the line 3—3 of Fig. 2, illustrating said rod more in detail and particularly its angularly disposed and bifurcated end portion as it contacts with said member, also a spindle installed in the member and an air vent for the bottle extending through the member.

35 Referring more particularly to the drawing, 1 denotes the bottle heretofore referred

to. Said valve member comprises a hollow base portion 2 adapted to fit over the neck of an ordinary bottle, a rubber gasket 3 being provided to give it a leak-tight connection therewith. 4 denotes a tube secured in said base portion, one end extending through the outer periphery of said portion and the other end extending within the bottle to a point adjacent the bottom thereof, to afford an air vent for the bottle. The inner end of the tube is so located as to prevent leakage under usual conditions, but to render leakage unlikely at all, the caliber of the tube is preferably small, or said end may be further restricted in size, if desired. A lug 5 is disposed on opposite sides of said base portion, the same being designed to prevent lateral displacement of the bifurcated end of said rod, as will hereinafter more particularly appear.

40 Surmounting said base portion is an elongated portion 6 having a bore-like opening 7 which extends for the major portion of its length and constitutes a valve chamber. Said opening also extends through said base portion and here it is interiorly threaded, as at 8, to accommodate a member 9 threadedly engaged therewith, which serves as a valve seat and is provided with an outlet port 10 for the bottle, said port communicating with the chamber 7. 11 designates a bore-like opening communicating with the chamber 7 and extending through the outer end of said portion 6, this second opening being of lesser diameter than the said chamber but in axial alignment therewith. A shoulder is thereby formed at the junction of the opening 11 with the chamber 7, said shoulder being denoted as 12. This shoulder, as it will be seen presently, functions as a valve seat as one of its 45 duties.

45 A valve spindle, generally denoted as 13, is mounted in the chamber 7 and opening 11, the same having a circumferential projection 14 which is normally seated on the shoulder 12. This projection is circular in outline, and as it may be noted in Fig. 2, is of a diameter slightly less than the chamber 7. A spiral spring 15 is disposed around the inner end 50 of said spindle and is mounted under com-

pression between the member 9 and the projection 14. The inner end 16 of the spindle is conical in form and is adapted to close the port 10 when the spindle is brought into operative engagement therewith. The outer end of the spindle is provided with a plurality of notches, each designated as 17, the same having sharp edges and designed to come in contact with the root of a plant and to crush the same. A segmental portion of said spindle is cut away to provide a longitudinal opening 18 between the spindle and the adjacent wall of the opening 11, as indicated in Fig. 3, and extending between the projection 14 and the outer end of the spindle, to permit the fluid from the bottle to flow freely from the valve member to the root of a plant when the valve is actuated for this purpose. The normal position of the valve mechanism described is particularly shown in Fig. 2.

A jointed rod 20, instrumental in operatively carrying said bottle and valve member, is provided. In the present embodiment of the invention this rod is in two parts secured together by a coupling 21 threadedly engaged therewith. A handle 22 is mounted on one end of the rod, and the other end of the rod has a portion bent, as at 23, to accommodate it to the adjacent curved surface of the bottle, as shown in Fig. 1, said portion terminating in a right angular bifurcated end 24. 25 denotes a threaded section of the rod on which is slidably mounted a clamping jaw 26, a winged nut 27 being threadedly engaged 35 with said section and operative on said jaw.

The bottle and the valve member mounted thereon as described are secured to the rod by first placing the bifurcated end of the rod on the base 2, locating it between the lugs 5 and 40 the portion 6. The clamping jaw 26 is then brought into contact with the bottom of the bottle and adjacent its edge and tightened in place by the winged nut 27. As will be evident, the bottle is held securely between said 45 end and the clamping jaw, as shown in Fig. 1, the threaded section 25, extending as it does for some distance along the rod, permitting the clamping jaw to be adjusted to bottles of various lengths.

50 In operating the device, it is assumed that the parts are assembled as shown and that a quantity of gasoline, or other suitable liquid, has been placed in the bottle. The spindle, being in the normal position indicated in Fig. 2, 55 said port 10 is open and free communication is established between the bottle and the chamber 7, with the result that the chamber is filled with said liquid. The user then adjusts the notched projecting end of the spindle to the root of the weed to be killed and exerts sufficient pressure on the handle of the device to crush the root. When pressure is thus applied the end 16 of the spindle engages the port 10, thereby closing it. The charge of liquid now contained in the chamber 7 will

flow therefrom downwardly and past the projection 14, being discharged from the chamber through the opening 18 whence it will run along the spindle until it reaches said root. When the device is lifted away 70 from the root the spindle will automatically return to its first position, the projection 14 again being seated on the shoulder 12 and obviously serving to close the chamber 7 from the opening 11. The spindle now being released from the said port 10 said chamber will be refilled with the liquid, and this cycle of operations may be repeated. As it will be seen, the charge of liquid for each operation is exactly the same, it amounting to the capacity of the chamber 7.

Changes in and modifications of the construction described may be made without departing from the spirit of my invention or sacrificing its advantages, hence I ask that I 85 be not confined to the specific structures set forth, except as limited by the appended claims.

I claim:

1. A weed killer, comprising a bottle, a 90 valve member, fitted over the top of the bottle, provided with valve mechanism operative on the bottle and having a sharpened valve spindle normally disposed in extended position, said mechanism being adapted to distribute liquid from the bottle and along said spindle when said spindle is retracted, means for preventing an air-lock in the bottle, a jointed rod carrying at one end a handle and at its other end a right angular bifurcated portion for embracing said member, a threaded section on said rod, a clamping jaw 95 slidably mounted on said section for engaging the bottom of said bottle, a winged nut bearing on said jaw, and said bottle and member clampingly secured to said rod between said jaw and said portion.

2. A weed killer, comprising a bottle, a top for the bottle having valve mechanism provided with a notched spindle for injecting 110 a liquid from the bottle into the roots of weeds, a rod carrying at one end a handle and at its other end a fixed clamping jaw for embracing said top, a movable clamping jaw mounted on said rod for engaging the bottom of said bottle, a nut threadedly engaged with said rod and bearing on said movable jaw, and said bottle and top clampingly secured between said jaws.

3. A weed killer, comprising a bottle, a 120 root-crushing and liquid-dispensing device fitted over the top of the bottle, a rod carrying at one end a handle and at its other end a fixed clamping jaw for engaging said device, a movable clamping jaw mounted on 125 said rod for engaging the bottom of said bottle, and means connected with the rod for bringing said jaws into tightened engagement with said bottle and device when the same are disposed between said jaws.

4. In a weed killer wherein an ordinary bottle is utilized as a container for a weed-killing fluid; instrumentalities adapted to be packaged in a compact knock-down condition, comprising a root-crushing and liquid-dispensing device adapted to be detachably mounted over the mouth of the bottle, a light-weight compactable supporting and handle member, and means whereby said bottle in an inverted position and with said device installed thereon may be detachably secured to said member.

5. A weed killer, comprising an assembly of a bottle and a root-crushing and liquid-dispensing device fitted over the mouth of the bottle, a supporting rod for said assembly carrying at one end a clamping jaw for engaging and retaining said device on the bottle and positioning said assembly relative to said rod, and means cooperating with the clamping jaw for securing the rod to the bottom of the bottle and operatively securing said assembly in place.
